UNITED STATES PATENT OFFICE.

WILLIAM B. SMITH WHALEY, OF MALDEN, MASSACHUSETTS, ASSIGNOR TO AMERICAN WHALEY ENGINE COMPANY, OF BOSTON, MASSACHUSETTS, A CORPORATION OF MASSACHUSETTS.

ENGINE-CONTROLLING APPARATUS.

Application filed December 20, 1917. Serial No. 208,031.

To all whom it may concern:

Be it known that I, WILLIAM B. SMITH WHALEY, a citizen of the United States, and resident of Malden, in the county of Middlesex and State of Massachusetts, have invented a new and useful Engine-Controlling Apparatus, of which the following is a specification.

This invention relates to engine controlling apparatus, and pertains more particularly to flexible control safety devices for separately and simultaneously manipulating actuating devices or elements designed to operate engines.

The invention has for its further objects and principles of operation, manipulating or controlling means whereby an operator or engineer cannot set all the engine actuating, controlling or operating elements into maximum operating position without first "stepping up," nor can the operator instantly reverse the operation of an internal combustion engine of the reversible type and by such act instantly set all said auxiliary devices in the full or maximum operating position. Especially in the latter case, the act of manipulating the main reversing elements will operate automatically to change the setting of other and dependent mechanisms to the minimum value of setting and to compel the operator to "step up" other elements to advance the point of ignition and for example, to close, if desired, the throttle controlling the precompression of the combustible mixture. Each reversing operation of the device will automatically "step down" the associated engine controlling elements and compel the operator to again "step up" the said associated engine controlling or operating elements in order to attain normal or maximum operating conditions thereof.

The invention is applicable to large or small engines, or engines having any number of cylinders or combinations thereof, and to any and all types or classes of engines. It is especially applicable to large units of internal combustion engines of any cycle of operation and whether horizontal or vertical, to control the settings and operation of auxiliary apparatus or devices.

In order to illustrate the principles and operation of my invention I have shown in the accompanying drawings but a single embodiment thereof applied to but one type of

an internal combustion engine which is selected for convenience merely.

In the drawings:

Fig. 1 is a side elevation of an engine described herein with my invention applied thereto.

Fig. 2 is a central vertical section on line 2—2 on Fig. 1 looking in the direction of the arrows.

Fig. 2^a is an enlarged view of the igniter operating mechanism shown in Fig. 2.

Fig. 3 is a partial elevation of the cylinder on the right hand end of Fig. 1.

Fig. 4 is a vertical sectional view illustrating somewhat diagrammatically throttling elements hereinafter described.

Fig. 5 is an enlarged detail plan of elements controlling auxiliary operating devices of the engine disclosed herein.

Fig. 6 is an enlarged elevation in detail of the controlling levers and associated elements of my invention in neutral position to illustrate more clearly the same devices embodied in Fig. 2.

Fig. 7 is an enlarged horizontal section on line 7—7 on Fig. 6.

Fig. 8 is an enlarged section on line 8—8 on Fig. 6.

Fig. 9 is an enlarged right hand elevation of Fig. 6, illustrating more clearly the same elements embodied in Fig. 1.

Figs. 10, 11 and 12 represent, respectively, a reversing lever, a throttling lever, and an ignition lever described herein.

Figs. 13 to 16 inclusive are enlarged detailed diagrammatic views representing different settings of controlling mechanisms employed for illustrating the principles of the invention, with said mechanism advanced from the neutral position to the position for forward running of the engine.

Figs. 17 to 20 inclusive are enlarged detailed diagrammatic views representing different settings of controlling mechanisms employed for illustrating the principles of the invention, with said mechanisms advanced from the neutral position to the position for reverse running of the engine.

The type of engine selected for illustration and the application of this embodiment of the invention, is a self-starting, reversing, marine engine of the vertical multi-cylinder two-cycle retarded combustion type, more specifically described in my co-

- pending application Serial No. 138,207, except that herein I have shown an engine having a plurality of cylinders in order to disclose the application thereto of co-operating or associated features or elements; also showing a change from the regulatable transfer valve to bypassing and regulating or throttling means between cylinders. It is to be understood that the invention is not limited in its application to this or to any other type or class of engine. Therefore, the embodiment of the invention and the terms employed herein to describe the same are used in the generic and descriptive sense to designate elements and not for the purpose of imposing limitations upon the invention.

In the drawings, the numerals 20 to 23 inclusive designate the vertical cylinders secured to the frames 24 to 27, respectively, in any suitable and well-known manner. The lower ends of said frames are in turn bolted or otherwise fastened to the single bed or base 28 suitably supported upon a foundation best adapted for the purposes of the engine. The base 28 is provided with bearings 29 in which is rotated the usual crank-shaft 30 provided with four cranks each co-operating with the usual connecting rod trunnioned to the cross-head of a piston rod having secured at the opposite end a piston preferably of the "skirt" type. As set forth in said co-pending application, the lower portion herein of each of the cylinders is provided with a precompression chamber with provision of means in the nature of transfer ports for directing the pre-compressed enriched carboniferous mixture from the said precompression chamber to the combustion chamber of each cylinder. Said enriched mixture is lacking in sufficient oxygen for the consumption of the entire carboniferous matter. If no more air is allowed to combine, there would result the burning of so much of the carboniferous matter as would take up the oxygen then present. Therefore, at a certain stage of the said cycle after ignition the additional air is admitted to combine with the balance of said carboniferous matter as to permit of the consumption thereof.

Referring first to the admission and control of the hydrocarbon, the same is produced in any suitable manner and conducted through the pipe 32 to the proportioning or regulating valve 33 from which it is admitted to the mixer 34. Air in the proportion of four parts to one part hydrocarbon or gas is now mixed with the latter to provide an enriched mixture. A manifold 37 connected to the said mixer 34 is provided with branching pipes 38 each leading to the precompression chamber 39 of a cylinder to now convey the enriched mixture to said chamber. Said precompression chamber 39

is similar in its functions to the compression chamber of any two-cycle internal combustion engine wherein the mixture is first compressed in the crank case or the like. Likewise, some internal combustion engines have provision of means termed a precompression chamber as in this instance for first compressing the mixture in an enclosing portion beneath the piston.

From said precompression chamber 39 the mixture is now conducted through transfer ports to the usual combustion chamber above the piston in each cylinder where at the proper time ignition takes place.

In the form herein illustrated, the cylinders are grouped in pairs; that is, cylinders 20 and 21 form one pair and cylinders 22 and 23 form another pair. Likewise, the cranks for the cylinders 20 and 21 have an angular relation of 180° so that when one piston is up on head-end-dead-center the other piston is down at crank-end-dead-center of each stroke thereof. This same arrangement is carried out with relation to the cylinders 22 and 23, but the cranks for the first pair of cylinders are 90° circumferentially from the cranks of the second pair of cylinders. Therefore, the piston in cylinder 20, when in its uppermost or head-and-dead-center position, is ready for ignition and to compress a charge in the precompression chamber, while the piston in cylinder 21 is now in position to receive a charge of the mixture from the precompression chamber 39 for further compression; said charge being forced into the combustion chamber through said transfer ports and at the same time it will be understood that the burnt gases have been exhausted.

When first starting the engine, it is desirable that the precompression pressure be relieved or reduced, which is accomplished herein by bypassing the desired portion of the mixture from one cylinder to another of a pair as precompression takes place. When the engine attains the normal operating condition, the bypassing of the mixture should cease so that maximum compression should be had of the mixture in the precompression chamber before transferring the same to the respective combustion chamber. Therefore, means for bypassing from one of a pair of cylinders to the other cylinder with mechanism for throttling or regulating the amount of mixture to be bypassed or for entirely stopping such operation is desirable. Herein, for example, a bypass pipe 40 communicates with the precompression chambers of the cylinders 20 and 21 and interposed somewhere between said cylinders is a bypass or throttling valve 41 for regulating the volume to be passed, or for entirely stopping the same. Referring to Figs. 1 and 4, where interposed between the cylinders 20 and 21 and connected to the pipe 40 is said

bypass valve 41, comprising a parted valve casing 42 to enclose therein the gate-valve 43 secured to the shaft 44 passing through a suitable bearing or gland 45. The gate valve 43 is adapted to swing laterally across and away from interiorly arranged ports or openings 46 at each side of the casing 42. Therefore, in Fig. 4 the full line position of the gate valve 43 indicates that the same 10 is open or exposes the ports 46 for the mixture to pass from one precompression chamber to another as the strokes of the pistons in the cylinders 20 and 21 alternate. The dotted line position in said figure shows full 15 closing of the valve 43 so that no mixture can pass from one precompression chamber to another. The precompression chamber is designated as 39 and the displacer or the like 47 is formed below the piston to project therein to reduce the volume of the lower part of the piston as the latter reaches the lowest point of the stroke.

The shaft 44 is continued to the same relative position between the cylinders 22 and 25 23, wherein may be found a similar by-pass or throttling valve 48 operating in the same manner as the one just described, except that the casing thereof is left-handed and reversed to that of valve 41.

30 The carboniferous mixture as first admitted from the precompression chamber to the combustion chamber, as before stated, is too rich and additional oxygen is later admitted to complete the functions of the cycle. For this purpose a source of compressed air supply is had from an auxiliary compressor or the like (not shown), and which is delivered by means of the pipe 50 to the compressed air admitting valve 52. 35 40 The said valve 52 is provided with a casing suitably secured to a cylinder in any suitable manner, as shown in the respective figures, and is preferably provided with a ported valve sleeve not shown herein but 45 more fully disclosed in said prior application Serial No. 138,207. Within said casing are ports and a sleeve member open to a chamber which is open to and discharges into a coacting valve casing having a chamber 50 and provided with a poppet valve communicating directly with the interior of the combustion chamber of a cylinder.

55 Referring specifically to Figs. 1, 2, 2^a, and 13 to 20 inclusive, the valve sleeve member is provided with a valve stem 55 connected by means of a link 56 to the arm 57 upon a rocking member 58 oscillatable upon a stud 59 secured in any suitable or preferred manner to a frame or the like 60 secured to the cylinder 21. Said rocking member 58 is likewise provided with an arm 61 connected with the control apparatus forming part of my invention, as will be hereinafter described.

65 Another crank arm 66 on the rocking

member 58 is pivoted at 67 to a link 68 fulcrumed at 69 to the free end of the tripper latch 70 adapted to operate an oscillating type of high tension impulse ignition generator, as the "Bosch" igniter, for example. 70 The tripper latch 70 is in turn pivoted at 71 to the journaled timing member 72 bearing on the elongated sleeve portion 73 of the rocking member 58. A crank arm 75 on said rocking member 58 is pivoted at 76 to 75 the cam link 77 and the opposite end of the latter is pivoted at 78 to the connecting link 79 in turn pivoted at 80 to the timing member 72. The cam link 77 has thereon a cam portion 82 adapted to engage with the operating means or impulse member 83 of the reciprocating type of high tension ignition generator 84 as the "Wyco" ignition for example. The timing member 72 is provided with an actuating arm 85 which is in 80 turn operated by mechanism of my invention as will be hereinafter described. The "Bosch" impulse ignition generator 86 is provided with the oscillating tripper arm 87 adapted to be engaged by the tripper 90 latch 70. The details of construction and organization of the mechanism of the different types of igniters referred to herein, are more fully set forth in my co-pending application Serial No. 199,813, which is referred to for a full understanding of such mechanism.

95 From the "Wyco" igniter 84 is a lead wire 94 connected to the spark plug 95 secured to the head of the cylinder 21 in the well-known manner. Likewise, the "Bosch" ignition generator 86 has connected thereto the lead wire 97 joined to the spark plug 98 secured into the head of the said cylinder. Therefore, each cylinder is provided with 100 two spark plugs which in large internal combustion engine units are desirable for complete ignition and to provide for certainty of ignition.

105 After ignition and combustion have been carried out in the complete cycle of operation of this particular type of engine the burnt or consumed products of combustion are passed from the cylinders through the branches 90 of the exhaust manifold 91 and 110 therefrom exhausted in the usual manner.

In the operation of the engine, however, it is desirable and especially in large units it is essential to properly and efficiently control the operation of the auxiliary devices, 115 more especially is it so in the case of reversible engines. Said control must be instantly available during all the time of operation of the engine to enable the operator to manipulate said auxiliary devices for the purpose 120 of stopping, reversing and to start the engine.

125 To accomplish the above, I herein provide reversing valve gear mechanism for the operation of the compressed air admitting 130

valve 52 to operate the igniters 84 and 86 and associated with the control of said valve gear I also provide means for actuating the throttling valves 41 and 48 to regulate the 5 precompressed mixture passed between each pair of cylinders as hereinbefore stated. Said valve gear is operated by the shaft 30 by means of the eccentrics 100 and 101 co-operating with the eccentric straps 102 and 103 on the eccentric rods 104 and 105 respectively. Said eccentric rods are pivoted at 107 and 108 on the segment 109 of a well-known and usual type. Said mechanism as just described, is known as the "Stephenson" valve gear and is well understood by those skilled in the art as adapted for reversing engines to operate the control valve associated therewith. Co-operating with the said segment 109 is a sliding block 110 upon 10 the end of a lever 112 secured to the shaft 113 journaled in bearings 114 on the frames 24 and 25. Also pivoted to the lever 112 is an actuating rod 116 pivoted at 117 to the lever 57 on the movable member 58. Therefore, the actuating rod 116 is operated by 20 the movement of the segment 109 depending upon the position of said segment relative to the slide block 110.

For operating the segment 109 to position 30 it relative to the slide block 110 for running ahead or running in the reverse direction or placing the same in the neutral position, a shifting gear mechanism is necessary.

35 Herein I provide a link 119 which is pivoted at 107 on the segment and at 120 to the arm 121 of a bell crank lever secured to the shaft 122 journaled in bearings 123 between the frames 25 and 26. The other arm 125 of 40 the said bell crank lever has pivoted thereto at 126 the reversing rod 127 also pivoted at 128 to the arm 129 upon the sleeve 130 integral with the reversing lever 131. The sleeve 130 of said reversing lever is rotatable 45 upon the stud 133 secured at 134 to the frame 25. Said reversing lever is provided with the usual latch 135 having a detent to engage with the notches 136 and 137 upon the quadrant 138 bolted at 139 to the spider 50 140 integral with the stud 133. Said reversing lever 131 is provided with a grip or handle 141 extending above and over the said quadrant 138. It is desired at this time to emphasize the fact that the said stud 55 133 and therefore the quadrant 137 are stationary in order to differentiate the same from associated quadrants that are adapted for movement or partial rotation and controlled by the operation of other mechanism 60 entering into the invention. Therefore, it will be understood that the lever 131 is oscillated or partially rotated upon the said stud 133 and that the movement thereof will be communicated to the reversing rod 65 127. Said movement will be communicated

to the bell crank arm 121 and 125 and thence to the link 119 to shift the segment 109 in the desired direction or position.

The stud 133 is provided with an extension 142, and rotatable thereon is the sleeve 70 143 provided with the spider arms 144 to the ends of which is bolted the throttle quadrant 145. Positioned between the throttle quadrant 145 and the sleeve 143 is the ignition quadrant 147 which is bolted 75 at 148 to the said spider arms 144. The sleeve 143 has integral therewith an arm 149 pivoted at 150 to a quadrant actuating link 151.

Said quadrant actuating link 151 is also 80 pivoted at 152 to the lever 153 also secured or keyed to the shaft 122. It will be noticed that the lever 153 is shorter than the bell crank arm 125 thereby imparting a differential motion to the quadrant actuating 85 link 151 when the reversing rod 127 is operated by the reversing lever 131. The movement of the quadrant actuating link 151 will be communicated to the spider 144 and to both the quadrants 145 and 147. 90

Co-operating with the throttle quadrant 145 is the throttle lever 155 rotatable at 156 on the sleeve 143. Said throttle lever is adapted for movement relative to the said throttle quadrant and to be engaged by a 95 latch 158 pivoted on the said lever. The latch 158 has a detent thereon to engage with the teeth 159 and 160 on the said quadrant. Said throttle lever has an extension 162 and pivoted thereto at 163 is the throttle 100 link 164 in turn pivoted at 165 to the lever 166 secured to the throttle shaft 44 at a point intermediate the cylinders 21 and 22. Therefore when the said throttle lever 155 is oscillated or partially rotated, the movement thereof is imparted to the link 164, the lever 166 and to the gates in the valves 41 and 48. When the quadrant 145 is oscillated by means of the quadrant actuating 105 link 151 or when the throttle lever 155 is oscillated either movement will be imparted to said gate valves. 110

Pivoted on the said sleeve 143 on the opposite side of the spider arms 144 and co-operating with the quadrant 147 is the ignition control lever 168. Said lever has pivoted thereto a latch 169 having a detent to co-operate with the notches 170 and 171 on the quadrant 147. Pivoted at 174 on the ignition lever 168 is the ignition control 115 link 175 extending upwardly and pivoted at 176 to a lever 177 secured to the shaft 178 extending clear across from the cylinder 20 to the cylinder 23 and supported in the bearings 179 formed upon the frames 24 to 125 27 inclusive. Said lever 177 is adapted to actuate the shaft 178 and in turn the lever 180 secured thereto. Pivoted at 181 at the end of said lever 180 is a link 182 having the opposite end thereof pivoted at 183 to the 130

lever 85 integral with the movable member 58.

It will here be noticed by referring to Figs. 1, 2 and 3 that certain corresponding elements of the devices shown used with the different cylinders of the engine are provided with similar reference numerals, excepting that with some the exponent "a" is used as in Figs. 1 and 3.

10 The parts thus numbered with the numerals having the exponents "a" are practically similar in design and function to the corresponding parts bearing the same numerals and without the exponents "a" and consequently it is not necessary to describe them further. In Fig. 3 the operating arm of the rocking member of the ignition operating device is numbered 184 and corresponds to the like part or arm 61 shown in Fig. 2, but is formed differently and is oppositely disposed to the arm 61 as shown. The reason for this being that the same structures and elements are utilized throughout upon the different cylinders but that due to 25 the placing of the auxiliary devices on oppositely facing sides of each pair of cylinders that the structures are reversed or are of right and left hand construction necessitating this change in the design of the said arm 184. Likewise, the other corresponding elements or parts are oppositely directed or arranged by reason of this right and left hand design. The functions in each case throughout the operations of all 30 the mechanisms are identical, the difference in each instance being, that as the cylinders are fired in sequence each pair of cylinders has provision for ignition at 180° between cranks of a pair and 90° between each group 35 of said pairs. It will also be understood that like the throttle lever 155 and the relation thereof to the quadrant 145 the ignition control lever 168 is movable relative to its quadrant 147 and each quadrant and lever may likewise be oscillated or partially rotated as a whole by the operation of the link 151. The throttle lever 155, the ignition lever 168 and the quadrants 145 and 147 form what may be termed a floating 40 unit control, each of which is adapted to be operated independently one from the other or set in a corresponding relation with respect to the reversing lever 131 when the latter is positioned or operated.

45 Referring to Fig. 1, there will be seen duplicated the eccentrics 185 and 186 to actuate the eccentric rods 187 and 188 connected to a segment 189 in a manner similar to that of the segment 109 and with all corresponding elements hereinbefore referred to, except that the arrangement of the eccentrics 185 and 186 is 90° from the eccentrics 100 and 101. The eccentrics 185 and 186 operating the eccentric rods 187 and 188 are so positioned on the shaft 30

as to control the actuating rods 116^a and their valve stems in the proper sequence for the timing of the pistons in the cylinders 22 and 23 and ignition therefor.

5 As before stated each cylinder is provided with a duplication of all elements or devices of either a right or left hand construction best suited to the position and timing of the cranks and therefore ignition. This said difference does not require any variation of, or other ignition lever or throttle lever arrangement than that herein stated. Thus it will be noted by referring to Figs. 1, 2 and 3 that cylinders 23 and 21 and 22 and 20 (Fig. 1) are provided with ignition 75 operating mechanism shown in Figs. 2 and 3, respectively.

70 The same levers control the operation of all the elements in the same manner and when the reversing lever is moved from one extreme position to the other the segments 109 and 189 are moved simultaneously but the different controlling elements of the auxiliary devices for each cylinder are thrown or set in position corresponding with the proper 80 relation thereof to its respective piston.

75 The application and operation of my invention is as follows:

85 First, I will assume that the engine has been standing and is "cold" or has never been operated. Therefore, the first operations to be performed are to get the engine turning over, say in the "forward" direction for the purpose of admitting a charge in the precompression chambers for precompression and thence transferring the same to the cylinders. I will also assume that the controlling devices hereinbefore described, are in what may be termed the "neutral" position; that is, the reversing lever 131 is intermediate the ends of the quadrant 138 and is in what may be termed herein the neutral zone. Said neutral zone is, say, for example, 90 221° on either side of the mid-position of said reversing lever, as shown in Fig. 6. 100 Beyond the said neutral zone and at the first position of operation in either direction, the notches 136 and 137 are extended to the limits of movement of the said reversing lever with respect to the said quadrant. 105 During the movement of the reversing lever 131 through the said neutral zone, the movement of the reversing rod 127 is imparted to the arm 125 of the bell crank lever and to the arm 121, but such movement is 110 not enough to shift the segment 109 relative to the slide block 110 sufficiently to cause the actuating rod 116 to move the valve stem 55 and move the air admitting valve 52 the proper distance to cause the ports thereof 115 to open or be communicated with the source of air supply 50 to permit of air entering into the coating chamber, thence to be admitted past the hereinbefore stated poppet valve to the combustion chamber of the cyl- 120 125 130

inder. In fact, the said air admitting valve will not uncover the ports as the eccentrics are timed to open the air valve in the last or lower one-fifth of its stroke which is substantially 5° beyond the stroke of a piston in its cylinder taken from the head end. The air admitting valve will close its ports or means of communication from the pipe 50 to the co-operating poppet valve chamber 10 at substantially 100° beyond the point above referred to.

Therefore, the reversing lever 131 is now moved in the forward running position so that the detent of the latch 135 will engage 15 with the first of the notches 137, as shown in Fig. 13, in full lines. Assuming that at this time the throttling lever 155 and the ignition lever 168 are in the mid-position therefore, the movement of the reversing lever will 20 be communicated thereto but said levers 155 and 168 are still within the neutral zone setting ignition for late and the throttle valve 43 and corresponding valve are open for bypassing. From this point to full "forward" 25 said actuating rod 116 will move the valve stem 55 so that air from the pipe 50 will pass through the said air admitting valve to be discharged into the coating poppet valve chamber provided with the said poppet 30 valve. The pressure of the entering air will cause the said poppet valve to lift from its seat and the compressed air will enter the combustion chamber above the piston and forces the piston downward. As the said 35 piston is moving downward, one of the other pistons moves upward uncovering the intake ports to permit the carboniferous mixture being drawn from the manifold 37 into its precompression chamber while the air continues to be admitted to the cylinder first 40 stated until the latter has been cut off. The other pistons will be traveling in their respective cylinders and will commence to draw in charges of the carboniferous mixture 45 in the proper and successive order. Said compressed air supply is admitted to the next operating cylinder to force its piston down in the same manner, and so on. By this time the first cylinder will have exhausted 50 itself of the starting air and the carboniferous mixture will now be passed through its transfer ports from the precompression chamber to a point above the piston head or piston where it will be again compressed as 55 the piston moves up to the point of maximum stroke after which it will be ignited and the combustion cycle will commence to be carried out. This will reoccur in successive order according to the arrangement of 60 the cranks and pistons for such cylinder. The throttling lever 155 and the ignition lever 168 were moved in the same direction as the reversing lever 131 when the latter was shifted for starting. When the said reversing lever is moved to the extreme for-

ward running position the other or secondary levers above stated will have been moved by the quadrants 145 and 147 to the limit of the neutral zone in that direction. The said valve 43 and corresponding valve are in the 70 open position and ignition is set for late timing. The throttling lever 155 may now be moved relative to the quadrant 145 so that the latch 158 with its detent will engage the notches 160 beyond the neutral zone on the 75 said quadrant 138. When the latch 158 engages with the teeth 160 the gate-valve 43 will have been moved so as to wholly or partially cover the ports 46.

When the valve 43 and corresponding 80 valve are open the precompression pressure is reduced or relieved from one of a pair of the cylinder to the other as the piston of one is moving down and the other is moving up, it being remembered that this arrangement is carried out by placing each crank of the pair at 180° from the other. When the engine attains the desired speed, the said valves are closed by moving the throttle lever 155 to the full forward position and 85 the power of the engine is increased.

The manner in which the throttle lever 168 controls the throttle valve 43 and corresponding valve is by means of the rod 164 connected to the said throttle lever and to 90 the lever 166 secured to the shaft 44 partially rotating the same and the said valve.

Having described how a charge of carboniferous matter is admitted to the combustion chambers for ignition, I will now 100 describe the ignition actions and elements controlling the same. The eccentrics 100 and 101 being rotatable communicate the movement thereof to the eccentric rods 104 and 105 to actuate the segment 109 and the 105 actuating rod 116, as before stated, which movement is communicated to the arm 57 on the movable member 58. This operation causes the arms 66 and 76 to move correspondingly and the link 68 is pulled in one 110 direction, causing the tripper latch 70 to engage with the tripper arm 87 on the "Bosch" igniter or ignition generator 86 moving therewith until said arm slips off the said latch 70. The spring arrangement 115 co-operating with said arm, now causes the rotor of the generator to move or return suddenly, relative to the magnetic field of said igniter, inducing a current in the rotor and to the lead wire 97 to the spark plug 98. 120 The lever 77 also moves the cam 82 engaging with the movable member 83 of the Wyo igniter 84 until the said movable member reaches a point where the tripper mechanism therein operates to release the same 125 and the magnetic field, causing the latter to return suddenly, thereby inducing a current in the said coils which is carried by the wire 94 to the spark plug 95. Thus the charge in a combustion chamber is ignited, 130

but it is immaterial at this point to state whether or not it is early or late, except that in the preferred operation of the engine when starting there would be had what is known as late ignition.

By reason of the eccentrics 100 and 101 operating the lever 112, the actuating rod 116 controlled thereby causes reciprocating movement of the valve stem 55 with corresponding movement of the air admitting valve. When the movement of the latter reaches a position corresponding to a point 5° beyond the normal or early ignition point, air is admitted by said valve from the source of supply or pipe 50 to the intervening chamber between the aforesaid valve and the poppet valve. After ignition the enriched mixture will not burn throughout the entire downward movement of the piston, and as the piston advances the drop in pressure of the then burning gases to a point just below equalization with the pressure of the compressed air will allow or permit said compressed air to unseat the poppet valve to admit the air until the air admitting valve closes and the intervening chamber is practically empty for the purpose of supplying enough oxygen for complete and continued burning throughout the combustion cycle and for thereafter stratifying the burnt gases previous to exhaust.

The eccentric rods 104 and 105 continually operate the segment 109, the lever 112 and actuate the rod 116 to carry out successively and in the proper sequence of the movement of the aforesaid air admitting valve and to oscillate the movable member 58 to carry on ignition at the proper times. The engine now being in full operating condition will admit and precompress a fuel charge in each precompression chamber and from there transfer the same to the combustion chambers through the transfer ports in the order or sequence in which the different pistons are designed to operate. Ignition also is carried out at the proper times within each cylinder which is provided with its own latch block and ignition mechanism.

After the engine is in full operation, the reversing lever 131 may be advanced to its maximum position relative to the quadrant 138. When the reversing lever was moved from the neutral zone to the full ahead position, the link 127 imparted such motion to the bell crank lever 125 and caused the shaft 122 to partially rotate imparting the same to the lever 153 and to the link 151 which is in turn communicated to the arm 149 on the sleeve 143 causing the quadrants 145 and 147 to move in the same general direction in a differential manner so as to prolong the shortened neutral zones on said quadrants to the corresponding point relative to the quadrant 138. Therefore, the

throttle lever 155 moves correspondingly as shown in Fig. 13 as compared with Fig. 6, and from this point on the throttle lever may be advanced until the latch 158 engages with the notches 160 moving the link 164 to cause the valve 43 and corresponding valve to close over the ports 46. In other words, when the throttle lever is within the neutral zone, the valve 43 is in the open position and will remain open through the movement of the throttle lever in the neutral zone, and thereafter said lever 155 may be independently advanced from the said neutral zone and the valve 43 thereby moves to partially or entirely close the passage between said ports, depending upon what position the said throttle lever is left standing or is set. In said Fig. 13 the reversing lever 131 is positioned to set the air admitting valve to admit air to the combustion chamber and if the engine has been idle it would start operating on the air for forward running. The position of the throttle lever 155 is set within the neutral zone and the valve 43 and corresponding valve are in the open position so that no precompression can be had and consequently no appreciable transfer can be effected. Also, the ignition lever 168 being within said zone, has so positioned the timing member 72 that ignition cannot take place to be effective. Therefore, so far as the engine operating on the combustion cycle is concerned, the same cannot take place and the engine is inoperative relative thereto.

In Fig. 14 the reversing lever 131 is shown as advanced just beyond the neutral zone, while the throttle lever 155 has been advanced (see full line position) to a position to cause the link 164 to move the shaft 44 and rotate the said valve 43 to entirely close the passage between the ports 46. The ignition lever 168 has been moved to the full line position in Fig. 14, thereby actuating the link 175 pulling it downward and drawing with it the lever 180, changing it from the Fig. 13 position to the full line position in said Fig. 14. This pulls the link 182 downward, causing the lever 184 to move in the same direction, changing the position of the timing member 58 from maximum late to the early ignition position. In said figure, as shown in dotted lines, the position of the throttle lever shows that it has been moved to the right hand end of the quadrant, thereby opening the throttle valve 43 and corresponding valve.

It will be observed when the reversing lever 131 is in the full line position in Fig. 14, that the manipulation of either the throttle lever 155 or the ignition lever 168 or both beyond the right of the neutral zone on the quadrants therefor, as shown in dotted lines, will not yield effective operating results from the auxiliary devices

controlled by said levers 155 and 168. Therefore, for forward running of the engine all effective manipulation of said levers must take place to the left of the neutral zones on the quadrants for the levers.

Compare Figs. 13 and 14 wherein the reversing lever 131 is set for forward running, partially shifting the segment 109 but the throttle lever 155 and ignition lever 168 have been advanced from Fig. 13 to the position in Fig. 14 to fully close the throttle and time the ignition devices for early ignition. Leaving the throttle lever 155 and ignition lever 168 in the mid or neutral positions, as in Fig. 13, and advancing the reversing lever to the full forward position, as is illustrated in Fig. 15, the same effect will be had but to a lesser degree than that of placing the said levers in the full line positions indicated in Fig. 14. In other words, by moving the reversing lever from the position illustrated in Fig. 13 to the position in Fig. 15 the operator has closed the throttle valve 43 and corresponding valve and has advanced ignition from maximum late to early ignition. At the time of this movement the link 127 has moved the arms 121 and 125 of the bell crank to place the segment 109 in position to give a longer stroke to the lever 112 and the actuating link 116. This longer stroke is communicated both to the air admitting valve and to the movable member 58 making a slight change in the operation of the tripper latch 70 and the cam 82. If the said throttle lever 155 and the ignition lever 168 are maintained in the neutral position as in Fig. 15 and the reversing lever is moved to the right as in Fig. 16 to a point within the neutral zone, the effect of the same will be to shift the segment 109 toward the mid-position relative to the slide-block on the lever 112 so that practically no reciprocating movement will be had. The quadrants 145 and 147 are likewise shifted communicating this movement to the levers 155 and 168 to move the valve 43 and corresponding valve so as to uncover the ports 46 and shift the lever 180, and therefore, the timing member 58 into maximum late ignition position and the engine will cease its operation. Therefore, it will be seen that the positions of the quadrants 145 and 147 are dependent upon the position of the reversing lever 131 relative to its quadrant 138. The throttle lever 155 and the ignition lever 168 are each capable of independent adjustment or regulation to open or close the throttle and to advance or retard the ignition from maximum late to early ignition. Any change of the position of the reversing lever 131 will produce a simultaneous and corresponding change in both the throttle lever 155 and the ignition lever 168.

65 By referring to Fig. 17 it will be seen

that the throttle lever and ignition lever 155 and 168, respectively, remaining within the neutral zone, that further movement of the reversing lever to the right to engage with the notches 136 will move the quadrants 145 and 147 in the same direction by reason of the aforesaid links 127 and 151 and the arms 125 and 143. In said figure the reversing lever 131 has moved the segment 109 relative to the slide-block but on the other side of the said segment for reverse running or operation of the engine. The actuating link 116 has placed the compressed air admitting valve for the reverse operation thereof as distinguished from that in Fig. 13 as hereinbefore stated. Likewise, the ignition latch block members referring to the operating mechanism for the ignition devices have changed their positions so as to cause the same to operate the ignition device at a point corresponding to 180° or opposite from that hereinbefore described. It will be noticed in particular that if the throttle lever 155 and the ignition lever 168 are positioned to the left of the mid-position upon their respective quadrants, that when the reversing lever 131 is shifted in the reverse operating direction of the engine, as just described, there results an opposite setting of said throttle and ignition lever. In other words, if the said throttle and ignition levers are to the left, as in Fig. 14, while the reversing lever is beyond the neutral zone, as indicated in said figure, that the said two levers 155 and 168 are set to close the valve 43 and have advanced the spark, but that if these two levers 155 and 168 are retained in this position and the operator throws the reversing lever 131 entirely to the right past the neutral zone to engage with the notches 136, that there automatically results reversal operations, to wit, the opening of the valve 43 and maximum late ignition. The shifting of the reversing lever 131 from one extreme to the other of the quadrant 138 automatically causes an opposite setting of the throttle and ignition devices and that further adjustment must of necessity be had to bring the engine to operating condition after the said reversing lever has been thrown into the reverse position. The operator therefore is required to again "step up" or to close the throttle valve 43 and to again advance ignition from late to early by operating both the throttling lever 155 and ignition lever 168 independently of the then position of the reversing lever 131. In this case the throttle lever 155 and ignition lever 168 must be moved to the right for effective operation of the auxiliary devices. Therefore, when the throttle lever 155 and the ignition lever 168 are in the mid-position of the neutral zone, as shown in Fig. 5, with relation to their respective quadrants, the valve 43 and the corresponding valve are open and

the ignition apparatus is set for maximum late ignition. In Fig. 17, while so retained in said position, the reversing lever 131 has been moved to engage with the notches 136. 5 The said valve 43 and corresponding valve are still open and late ignition still takes place. In Fig. 18, the reversing lever 131 has been further advanced, while the said throttle lever and ignition levers are still 10 within the neutral zones on their respective quadrants. The valve 43 and corresponding valve are partially closed and ignition has been "stepped up" to slightly advance the same towards early ignition. The segment 15 109 has been moved further to the left, imparting greater movement or stroke to the actuating rod 116 and the compressed air admission valve.

Then in Fig. 19, the reversing lever 131 is maintained in the same relative position as in Fig. 18 but the throttle lever 155 has been advanced to so position the valve 43 and corresponding valve as to entirely cut off bypassing between the cylinders of a 25 pair while the ignition lever 168 has been advanced to its extreme position for very early ignition. In Fig. 20 the throttle and ignition levers are in substantially the same position as Fig. 19 with respect to their 30 quadrants but the reversing lever 131 has been shifted within the neutral zone in which the engine is inoperative; a similar condition is to be found with respect to Fig. 16. The quadrants 145 and 147 have heretofore been moved by the said operation 35 of said reversing lever so that they are now set towards the neutral zone and the valve 43 and the corresponding valve are still closed and ignition has been retarded. 40 The segment 109 has been shifted so that there is virtually no stroke of the actuating rod 116 and the compressed air-admitting valve is not getting enough movement to open the ports between the same and the 45 source of supply 50. Likewise, said stroke is insufficient to operate the ignition devices.

Thus it will be seen that any movement of the reversing lever will automatically impart corresponding movement to the quadrants 145 and 147 and to the levers 155 and 168 thereby producing relative movement of the valve 43 and the corresponding valve; likewise producing relative movement of 55 the timing member 72. When within the neutral zone of movement, the reversing lever 131 when operated will not produce sufficient action of the segment 109 and the quadrants 145 and 147 to cause the engine 60 to start or to operate unless the reversing lever is positioned beyond the neutral zone for forward or reverse running. When the throttle lever 155 and the ignition lever 168 are within their own neutral zones or 65 in the mid-position relative to their re-

spective quadrants then whether or not the reversing lever 131 is set for running ahead or for reverse running the valve 43 and the corresponding valve are open for bypassing, and ignition takes place very late 70 in the stroke.

The operator therefore cannot throw the reversing lever from one extreme position to the other without automatically changing the throttling lever and ignition lever 75 from a "step up" position to a "step down" position, requiring that he again "step up" the latter to attain maximum operating conditions.

While I have shown and described herein 80 mechanism adapted to operate reversing gear and an air admission valve and adapted to automatically and simultaneously regulate throttling and ignition devices (all of which I term auxiliary devices), any 85 other auxiliary device or devices of a similar nature or kind may be operated, controlled or set by means of the same or a similar type of control elements to those herein. Any adjustable auxiliary devices 90 for any and all types of engines are included as within the scope of control by means of apparatus embodying the features and principles of my invention.

While I have shown and described the 95 reversing apparatus as a Stephenson link valve gear, any other gear system or mechanism capable of performing the same or similar functions and operations may be employed in conjunction with apparatus 100 of my invention.

It will be seen that the invention has for its further objects principles and elements assuring safety of control, putting outside of the province of the operator the care or 105 management of separate controlling devices, whereby in a moment of carelessness or thoughtlessness the wrong lever may be moved to produce harmful or injurious results. Each mechanism is automatically 110 and simultaneously adjusted to suit the new conditions brought about by the mere operation of reversing, especially in the case of marine engines of large units where it is necessary that rapid operation shall be 115 had to suit any and all conditions under which a boat or the like is operated to provide for change of speed and rapid reversal of the direction of movement. Many other and similar conditions, situations or the 120 like of operation may be met with in other branches or uses where a reversing engine is required. The specific cases stated are set forth merely for the purpose of pointing out that such conditions are to be met 125 with.

When the levers 155 and 168 are in the position in Fig. 14, the lever 131 may be manipulated so as to automatically advance or retard ignition as the lever 131 is ad- 130

vanced or moved to neutral respectively; that is, as the lever 131 is advanced for forward running, ignition is advanced or set earlier and at the same time the 5 throttle valve is closing, and when the reverse operation is imparted to said lever 131 the ignition is retarded and the said valve tends to open. By this it may be seen that the invention would have its application 10 also to non-reversing engines.

The operator may, if necessary, employ both hands and manipulate the throttle lever with the reversing lever, or may operate the ignition lever simultaneously with 15 the reversing lever 131 instead of manipulating one lever at a time without interfering with the purpose of the invention by reason of the passage of all levers through the neutral zone or enforced pause 20 created thereby compelling further manipulation of the third lever.

I have described herein one embodiment of my invention, but it is to be understood that the latter is not essentially limited to 25 the specific construction and organization of said embodiment, since the same may be varied without departing from the proper scope of the claims.

Having thus described my invention in 30 detail, what I claim as new is:

1. In combination with an engine having a reversing valve gear mechanism, an ignition device, and a throttle device, a primary controlling element adapted to regulatably operate the reversing valve gear of said engine to yield any of the desired operating results therefrom, as starting, stopping, and controlling the speed of operation of the engine in either direction, a secondary controlling element adapted to regulate said ignition device, a secondary controlling element adapted to regulate said throttling device of said engine, said secondary elements having provision of means for independently regulating said devices, and connecting means between said valve gear mechanism and said secondary controlling elements for simultaneously regulating the said devices to conform to the regulations of said primary controlling element.

2. In combination with an engine having a reversing valve gear mechanism, an ignition device and a throttle device, an apparatus of the character described, comprising a primary controlling element adapted to control the reversing valve gear of said engine to yield any of the desired operating results therefrom, as starting, stopping, and controlling the speed of operation of the engine in either direction, a secondary controlling element adapted to regulate said ignition device, a secondary controlling element adapted to regulate the throttle device of said engine, and connecting means between said valve gear mechanism and the said sec-

ondary elements for controlling the latter to correspondingly regulate the same to conform to the regulations of the primary controlling element.

3. In combination with an engine having 70 a reversing valve gear mechanism and an ignition device, an apparatus of the character described, comprising a primary controlling element adapted to operate said valve gear mechanism to regulatably yield the 75 desired starting, stopping, and speed control in either direction of operation of the engine, a secondary controlling element adapted to control said ignition device, and connecting means between the valve gear 80 mechanism and the secondary controlling element for automatically advancing the ignition and for retarding ignition when the primary controlling element is reversed.

4. In combination with an engine having 85 a reversing valve gear mechanism, an ignition device and a throttle device, an apparatus of the character described, comprising a primary controlling element adapted to operate said valve gear mechanism to 90 regulatably yield the desired starting, stopping and speed control in either direction of operation of the engine, a secondary controlling element adapted to regulate said ignition device, a secondary controlling element adapted to regulate said throttling device, connecting means between said valve gear mechanism and said secondary controlling elements for automatically advancing the ignition when the primary element is 100 advanced and to close the throttle and to retard ignition and to open said throttle when the primary controlling element is reversed.

5. In a self-starting and reversing internal combustion engine having a reversing valve 105 gear mechanism operating an ignition device, a primary controlling element adapted to regulate said engine valve gear mechanism to yield the required operating functioning therefrom, as starting, stopping and controlling the speed of the engine in either of its directions, a secondary controlling element adapted to control and regulate said ignition device, and connecting means between said valve gear mechanism for automatically advancing ignition when the primary element is advanced and to retard ignition when said primary element is reversed.

6. In combination with an internal combustion engine having a valve gear and an auxiliary device, an apparatus of the character described, comprising a primary controlling element having a neutral zone of adjustment and adapted to control said valve gear of said engine when placed beyond said zone for regulatably controlling the starting, stopping and speed of the engine in either of its operating directions, a secondary controlling element adapted to independ- 120 125 130

ently control said auxiliary device on said engine, means connecting a part of said valve gear with said secondary controlling element whereby the movement of the former simultaneously regulates the latter through and beyond said neutral zone.

7. In combination with a reversible internal combustion engine having a reversible valve gear operating an auxiliary device, an apparatus of the character described, comprising a reversible primary controlling element having a neutral zone of adjustment and adapted to control the valve gear of said engine and to regulate a secondary controlling element between which the starting, stopping and speed of the engine may be regulatably controlled in either direction of the engine, a secondary controlling element adapted to independently regulate said auxiliary device after movement has been imparted thereto by the primary element.

8. In combination with a reversible internal combustion engine having a reversible valve gear mechanism and different auxiliary devices, an apparatus of the character described adapted to regulate the starting, stopping and speed operation of the engine in either direction, and comprising a primary controlling element adapted to position said reversible valve gear mechanism of said engine, a plurality of secondary controlling elements each adapted to automatically function with said primary controlling element and to additionally independently regulate a different auxiliary device, lever means connecting the primary controlling element with the secondary controlling elements whereby the movement of the former will communicate bodily movement to the latter, said secondary controlling elements having lever means adapted to independently regulate said auxiliary device.

9. In an apparatus of the character described, in combination with a reversible retarded combustion engine having a reversible valve gear, a pair of movable quadrants, and ignition and throttling devices, a primary controlling member adapted to position the reversible valve gear of said engine and to regulate the position of said movable quadrants, a pair of regulating levers co-operating with the said quadrants and

adapted to be positioned thereby, one of said levers having provision of means for regulating the ignition device for said engine and the other of said levers having provision of means for regulating the throttling device for said engine.

10. In an apparatus of the character described, an engine having a reversible valve gear, a stationary quadrant, a pair of movable quadrants, and variable ignition control and throttling apparatus, a reversing lever co-operating with said stationary quadrant and having means whereby said lever reversibly regulates said co-acting reversible valve gear for said engine and regulates said movable quadrants when said lever is operated, a pair of secondary levers co-operating with said quadrants and adapted to be regulated thereby, one of said secondary levers having connecting means with said variable ignition control apparatus for regulating the latter and the other of said secondary levers having connecting means with said throttling device for regulating the same.

11. In an apparatus of the character described an engine having a reversible valve gear, a stationary quadrant, a pair of movable quadrants, a variable ignition control device, and a throttling device, a reversing lever co-operating with said stationary quadrant and having means whereby said lever reversibly regulates said co-acting reversible valve gear operating said variable ignition device and which lever regulates said pair of movable quadrants to position said quadrants when said lever is operated, a pair of secondary levers co-operating with said quadrants and adapted to be moved thereby, one of said secondary levers having connecting means with said variable ignition device and adapted to regulate the latter and the other of said secondary levers having connecting means with said throttling device for regulating the same.

In testimony whereof I have hereunto set my hand this seventeenth day of December, 1917.

WILLIAM B. SMITH WHALEY.
